UNITED STATES PATENT OFFICE.

HENRY VAN HOEVENBERGH, OF ELIZABETH, NEW JERSEY.

ELECTRO-MECHANICAL ESCAPEMENT.

SPECIFICATION forming part of Letters Patent No. 293,925, dated February 19, 1884.

Application filed April 30, 1883. (No model.)

To all whom it may concern.

Be it known that I, HENRY VAN HOEVENBERGH, a citizen of the United States, and a resident of Elizabeth, in the county of Union 5 and State of New Jersey, have invented certain new and useful Improvements in Electro-Mechanical Escapements for Printing-Telegraphs, of which the following is a specification.

10 My invention relates to the construction of the immediate devices for controlling the positions of the type-wheel of a printing-telegraph instrument during the operation of transmission.

15 The object of the invention is to render the action of such devices more rapid, and thus to impart greater speed to the type-wheel.

The invention consists in constructing the escapement device of a telegraphic printing- 20 instrument, with an armature and an armature-lever impelled in one direction through the attractive influence exerted by an electro-magnet included in the circuit of the transmitting device, and in the reverse direction 25 through the influence of an electro-magnet included in the circuit of a local battery, the connections of which are momentarily automatically completed when the armature responds to the influence of the first-named 30 electro-magnet.

In the accompanying drawing I have shown so much of the mechanism and circuits of a printing-telegraph system as is essential to a complete understanding of the invention.

35 Referring to the drawing, E represents the main battery of a printing-telegraph system, and K a transmitting device, which may be of any suitable well-known construction. One pole of the battery E is connected by a conductor, 1, with the earth at G, and the remaining pole is connected through the transmitting device K with the main line L, leading to the receiving-instrument at R. The main line L is connected through the coils of an 40 electro-magnet, M, in the receiving-instrument with the earth at G'. The movements of the type-wheel T of the receiving-instrument are controlled by an anchor-escapement, B, engaging the teeth of a toothed wheel, A. 45 The wheel A is carried upon an arbor, a, and

may normally be impelled in a given direction through the influence of any suitable mechanical or electrical device acting upon the arbor a; or it may depend for its advancement upon the movements of the device B. In 55 the latter instance the wheel A should be constructed in the form of a "star-wheel," and the pallets b of the anchor B would act as pawls for propelling the same step by step in a manner well understood. The anchor-escapement B is carried upon a lever, C, supported upon an arbor, c.

Upon the arm c' of the lever C, remote from the anchor B, is mounted the armature N of the electro-magnet M. A second electro-magnet, m, is applied to the armature N. This electro-magnet, when vitalized, exerts upon the armature N, and thus upon the lever C, a force opposed to that exerted by the electro-magnet M. The coils of the electro-magnet m 65 are included in the circuit 1 2 of a local battery, e. A circuit-closing device, D, interposed in this circuit, is arranged to complete the connections of the battery through the coils of the electro-magnet only at the time 70 when the armature N is attracted into proximity to the poles of the electro-magnet N.

The device D consists of a longitudinally-movable rod, d, carrying near one extremity an insulated contact point or surface, d'. The 80 extremity f of a contact-spring, F, connected with the conductor 1, leading from one pole of the battery e, normally rests upon the point d', and thus out of electrical connection with the rod d. The rod d is itself electrically connected through the conductor 2 with the remaining pole of the battery e. When, therefore, the rod d is in the position represented in the drawing, the circuit of the battery e 85 will be interrupted and the electro-magnet m 90 will not be vitalized. Two stops, d² and d³, are carried upon the rod d, and extend upon either side of the extremity of the arm c' of the lever C. When the lever C is actuated in one direction through the influence of the attraction exerted by the electro-magnet M upon the armature N, the arm c' will engage the stop d² and move the rod d toward the left-hand a sufficient distance to carry the insulated point d' beyond the extremity of the spring F. The 100

contact of the spring F with the conducting-surface of the rod d will thereupon complete the connections of the battery e, and the electro-magnet m will be vitalized and tend to draw the armature N toward itself, serving thus in lieu of a retractile spring. The force exerted by the electro-magnet m is preferably not sufficient to effect the movement of the armature N and lever C until the current vitalizing the electro-magnet M is interrupted or lessened. Immediately upon an interruption of this current or a sufficient diminution in its strength the armature N will respond to the attraction of the electro-magnet m. The rod d will thereupon be moved, by the arm c' impinging upon the stop d', to its former position, thereby interrupting the circuit through the coils of the electro-magnet m. The electro-magnet m serves thus in lieu of a retractile spring and combines with the successive vitalizations of the electro-magnet M to vibrate the lever C and escapement D in whatever manner is necessary for controlling the positions of the type-wheel.

It is evident that the parts may be so constructed that the circuit of the local battery e shall be completed or interrupted at any desired point in the excursion of the armature-lever. I am aware that it is not new to complete a circuit through a retracting-magnet by the contact of an armature-lever with its limiting-stop; but the retracting-force in such an organization is removed at the first movement of the armature-lever in response to the retracting-magnet by reason of the necessary interruption of the circuit therethrough, whereas in my construction that force may be continued through as great a proportion of the movement of the lever as desired, thus insuring a complete retraction of the armature.

I claim as my invention—

1. The combination, substantially as hereinbefore set forth, with a main battery and a transmitting device, of the type-wheel of a printing-telegraph instrument, an escapement-

wheel, a lever for controlling the movements of said escapement-wheel, an electro-magnet included in the circuit of said main battery for actuating said lever in one direction, an electro-magnet included in a local circuit for actuating said lever in the opposite direction, and means, substantially such as described, for automatically completing the connections of said local circuit when said lever is actuated in response to the first-named electro-magnet.

2. The combination, substantially as hereinbefore set forth, of the escapement of a printing-telegraph, an armature and armature-lever for actuating said escapement, an electro-magnet vitalized by currents from a distant station for actuating said armature and armature-lever in one direction, and an electro-magnet included in a local circuit for actuating said armature and armature-lever in the reverse direction.

3. The combination, substantially as hereinbefore set forth, of a main battery, an armature and armature-lever, an electro-magnet included in the circuit of said battery and acting, when vitalized, to impel said lever in a given direction, a local battery, a second electro-magnet included in the circuit of said local battery and tending, when vitalized, to impel said lever in the opposite direction, a stationary contact-point in electrical connection with one pole of said local battery, and a movable point electrically connected with the remaining pole of said local battery, said contact-points serving to complete the circuit of said local battery in the course of the passage of said armature-lever from one limit of its excursion to the other, and to interrupt said circuit during the course of movement of said lever in the opposite direction.

In testimony whereof I have hereunto subscribed my name this 25th day of April, A. D. 1883.

HENRY VAN HOEVENBERGH.
